BROADBAND TRAVELING-WAVE AMPLIFIER

Thomas E. Everhart, Santa Monica, Calif., assignor to Hughes Aircraft Company, Culver City, Calif., a corporation of Delaware

Filed July 22, 1955, Ser. No. 523,725

2 Claims. (Cl. 315—3)

This invention relates generally to traveling-wave tubes, and more particularly to an improved dispersive traveling-wave amplifier having a broadband frequency response.

In a traveling-wave tube, a slow-wave structure such as a helix is capable of propagating electromagnetic energy in several different modes. One of these modes represents the fundamental wave which has a phase and a group velocity in the forward direction. In an ordinary forward wave traveling-wave tube amplifier, an electron stream is directed along the slow-wave structure at a velocity slightly greater than the phase velocity of the fundamental wave in a manner to effect an interchange of energy from the electron stream to the wave to cause amplification of the wave. The frequency response of such an amplifier is quite broad. However, when it is desired to amplify a wave representing a mode of propagation whose phase velocity is in a direction opposite to that of the fundamental mode, i.e., a backward wave, the frequency response is very narrow band. This is because for a given voltage or velocity of the electron stream, there is only a very narrow band of frequencies in the backward wave which the electron stream will amplify or deliver energy to.

Heretofore broadening the frequency band was accomplished by having two or more helices or other anodes at different voltages which resulted in a stagger-tuned effect in which, although the response was indeed broadened, the magnitude of amplification of the backward wave was considerably decreased and was not constant over the bandwidth.

It is, therefore, an object of the present invention to provide a broadband traveling-wave tube having a multi-velocity electron beam while not suffering the disadvantages of stagger-tuned systems.

It is another object to provide in a broadband dispersive traveling-wave amplifier means for providing a multi-velocity electron stream having a square-wave distribution between two limiting velocities or voltages.

It is a further object to provide in a backward-wave amplifier such a multi-velocity electron stream from the equivalent of an infinite number of cathodes each at an infinitesimally different potential and ranging between the desired upper and lower limiting potentials.

It is still a further object to provide such a cathode arrangement which is practical and simple to fabricate and utilize.

Briefly, in accordance with the present invention, these objects are achieved in the following manner. A single cathode having a shape appropriate for forming an electron beam of the desired shape or cross section is used and is directly heated in a manner such that the heating current causes a continuous potential drop across the cathode which provides a continuous electron velocity distribution between the two limits of voltage the difference between which represents the total potential drop across the cathode.

In a conventional backward-wave amplifier the desired

2

beam shape is that of a hollow cylinder projected along the interior of a slow-wave structure such as a helix. In accordance with this invention, the cathode is ring shaped, the ring being severed at one point and having the desired potential difference applied to the separate ends of the ring across the gap; and this potential drop being appropriate to cause a heating current around the ring and to give the desired electron velocity distribution due to the difference in potential between successive areas of the cathode emissive surface and the accelerating anodes.

Another embodiment of the present invention is that of a sheet beam forming cathode as used in traveling-wave tube amplifiers of the type called traveling wave magnetrons in which a sheet beam electron stream is projected between a conductive plate and a conductive periodic slow-wave structure. The cathode shape in such a traveling-wave tube is an elongated rectangle disposed with the rectangular emissive surface perpendicular to the desired beam path; and in accordance with the present invention the emissive surface is directly heated by a potential drop along its length of a magnitude suitable to give the desired range of velocity distribution.

The novel features which are believed to be characteristic of the invention, both as to its organization and method of operation, together with further objects and advantages thereof, will be better understood from the following description considered in connection with the accompanying drawings in which an embodiment of the invention is illustrated by way of example. It is to be expressly understood, however, that the drawings are for the purpose of illustration and description only, and are not intended as a definition of the limits of the invention.

In the drawings:

Fig. 1 is a partially cut away schematic view of a typical backward wave traveling-wave tube amplifier utilizing a cathode structure in accordance with this invention;

Fig. 2 is an enlarged perspective view of one embodiment of a cathode structure of this invention as utilized in the example of Fig. 1;

Fig. 3 is a group of graphs to aid in the description of the operation of the invention; and

Figs. 4, 5, 6 and 7 are perspective views of other embodiments of the cathode structure of this invention.

Referring now to the figures, and particularly to Fig. 1, a backward-wave amplifier traveling-wave tube 10 is shown having an evacuated envelope 12 enclosing and supporting a slow-wave structure 14 and an electron gun 16. A collector electrode 18 is shown disposed at the end of glass envelope 12 opposite electron gun 16 and adapted to collect the electron beam and dissipate its kinetic energy. An input conductor 20 is coupled in a conventional manner to the collector end of slow-wave structure 14 and an output conductor 22 is coupled to the emitter end of slow-wave structure 14. Solenoid 24 encloses substantially all of the structure of tube 10 and is adapted to constrain, confine, and focus the electron beam along and within the conductive slow-wave structure 14.

Electron gun 16 comprises the annular, directly heated 60 cathode structure 26, focusing electrode 28, and accelerating anode 30. D.C. adjustable voltage source 32 is coupled across the severed ends of cathode ring 26. Accelerating voltage source 34 is also adjustable and is coupled to the positive terminal of voltage source 32. 65 Adjustable voltage source 36 is coupled to the accelerating anode 30 and the positive terminal of source 36 is grounded. Focusing electrode 28 is electrically coupled to cathode 26.

Referring to Fig. 2, annular cathode structure 26 is shown in more detail and a negative potential of V_1 is shown to be that at one end of the ring, while a different

negative potential V_2 is shown to exist at the other end of the ring by virtue of voltage source 32.

Referring to Fig. 3, curve 38 shows the dispersion relation of a conventional backward-wave amplifier having a unipotential cathode which is at the potential V_x corresponding to an RF frequency of f_x .

Graph 40 is a plot of the gain of such a conventional tube as a function of RF frequency; and the bandwidth for the unipotential cathode arrangement is shown to be very narrow. The gain bandpass curve shown at f_y on graph 40 illustrates the manner in which the dispersion characteristic of a conventional backward-wave amplifier provides a narrow bandpass which is critically dependent upon the electron velocity of the stream.

Graph 42 shows the results of stagger-tuning an ordinary backward-wave amplifier by utilizing two or more slow-wave structures such as helices and having them at different voltages which results in a broader bandwidth with a lower overall gain and an irregular bandpass amplitude. The lowering of gain when the stagger-tuning is utilized is inherent in that the total beam current passing through any one helix is all at the same velocity and cannot be increased without causing backward-wave oscillation.

Graph 44 plots the dispersion characteristic of the backward-wave amplifier of Fig. 1 in which the range of velocities shown between V_1 and V_2 results in a frequency range shown between f_1 and f_2 .

Graph 46 then shows the resulting bandwidth characteristic which is essentially rectangular with the range from f_1 to f_2 . The maximum gain is shown to be the same as that according to graph 40 because in this case the total current may be considerably increased without oscillation since the current passing through the slow-wave structure is made up of all velocities in the range determined by V_1 and V_2 .

In the operation of backward-wave amplifier tube 10, electron gun 16 emits an annular, cylindrical electron beam comprising electrons having velocities represented by the difference in potential between the particular region of cathode 26 from whence they were emitted and the potential on accelerating anode 30. Thus, it may be seen that around the periphery of the cathode 26 the elemental surface areas vary in potential in a continuous sequence. This different potential for each elemental surface area assures that the velocity of electrons emitted will likewise consist of equal sub-interval velocities which contain equal numbers of electrons. Different portions then of the electron stream each support the amplification of a different group of frequencies in the backward wave traveling along helix 14 to thus afford a broadband operation. As pointed out hereinbefore, each such portion of the electron stream may have a current just under the oscillation starting beam current for the respective group of frequencies to thus provide a high gain across the entire bandwidth, as shown on graph 46 in Fig. 3.

The magnitude of the bandwidth, shown on graph 46, is determined by the frequency difference between f_1 and f_2 which is in turn determined, via the dispersion characteristic shown on graph 44, by the voltage difference between V_1 and V_2 ; that is, the voltage magnitude of source 32. It is, therefore, seen that the bandwidth may be arbitrarily controlled by a device as simple as a potentiometer.

In like manner the position of the bandpass region along the frequency axis of graphs 44 and 46 may be arbitrarily controlled by the magnitude of adjustable voltage source 34 or 36; that is, by changing either or both of these voltages, the range V_1 to V_2 on the voltage axis of graph 44 may be shifted to "tune" the amplifier to the desired position along the frequency axis.

Thus there has been disclosed a dispersive traveling-wave amplifier which provides maximum gain over an arbitrarily broad bandpass which is arbitrarily positioned to a desired center frequency.

Fig. 4 shows a second embodiment of a cathode in accordance with the invention. Cathode 26' comprises a "ring" of n turns where n is any positive integer. Such a structure operates similarly to cathode 26 and is further adapted to "mix" the various electron velocities.

Fig. 5 shows a third embodiment of a cathode for a multi-velocity electron beam. Voltage source 32 is applied across a sheet beam forming cathode 27. As with cathode 26, the stream emitted has a velocity spread along the length of the cathode by virtue of the gradual potential drop across the cathode. Focusing electrode 29 and accelerating anode 31 are conventional and are adapted to produce an electron stream having the desired parameters for any particular application. "Block" 15 33 is a slow-wave circuit utilizing a multi-velocity rectangular electron beam as emitted by cathode 27.

Fig. 6 shows a second embodiment of the cathode of Fig. 5. Voltage source 32 is applied across a rectangular cathode comprising several sinuate turns for, analogously 20 to cathode 26', "mixing" the electron velocities in the sheet beam.

Fig. 7 illustrates a further embodiment of the cathode structure of this invention. Cathode 26'' is indirectly heated by filament 35 which is heated by current from 25 adjustable voltage source 32'. This embodiment is particularly adapted to provide an independence between total beam current and the magnitude of voltage source 32. In accordance with this embodiment, when the magnitude of voltage source 32 is increased to provide a greater potential drop across cathode 26'', the temperature and hence emission of the cathode tends to increase. This effect would ordinarily be undesirable, and is precluded by lowering the potential drop across heater filament 35 by decreasing the magnitude of voltage 30 source 32' in a manner to cancel any tendency to emit a greater beam current thus providing the desired independence between velocity spread and total beam current.

What is claimed is:

40 1. In a dispersive broadband backward-wave traveling-wave tube for propagating electromagnetic waves along a slow-wave structure and for effecting an interchange of energy between the waves and an electron stream projected along the slow-wave structure, a cathode device adapted to emit a multi-velocity electron stream having a predetermined velocity distribution, the cathode device comprising: a cathode having two spaced apart terminals and being adapted to be indirectly heated and to emit a predetermined total cathode beam current; a cathode heating means; and first and second variable voltage sources, said first voltage source being coupled between said terminals said cathode in a manner to provide the predetermined electron velocity distribution, said second voltage source being coupled to said heating means in a manner such that when the magnitude of voltage of said first voltage source is increased, the magnitude of voltage of said second voltage source may be concurrently decreased in a compensatory mode whereby said predetermined total cathode beam current may be held constant independent of the magnitude of voltage of said first voltage source.

60 2. In a dispersive traveling-wave tube, an electron gun of the character adapted to emit a multivelocity stream of electrons toward a slow-wave structure, the electron gun comprising: electron accelerating means spaced along said tube and maintained at a pre-determined accelerating potential; electron focusing means disposed about said tube and focusing the stream through said electron accelerating means; a variable potential voltage source for a cathode, said source providing different potentials which are negative with respect to said accelerating potential; a cathode having an emissive surface coupled to said voltage source, said cathode consisting of a unitary member having spaced apart terminals each of which is coupled to a different potential of said voltage source, thus

providing a continuous potential variation along said unitary cathode and said emissive surface between said cathode terminals, the potential levels of said voltage source being selected with respect to said predetermined accelerating potential so that the electrons emitted have a velocity distribution which is continuous between minimum and maximum velocities thus providing in the traveling-wave tube a frequency band of operation determined by said voltage source levels and said accelerating potential; auxiliary heating means for said cathode; and an adjustable voltage source connected to said heating means for determining the magnitude of heating effect for maintaining the total electron current in said multi-velocity stream of electrons constant regardless of the magnitude of the potential difference applied to the terminals of said cathode.
